FLUID DEFLECTOR FOR WELL DRILLS

Floyd L. Scott, Houston, Tex., assignor to Hughes
Tool Company, Houston, Tex., a corporation of
Delaware

Application February 27, 1940, Serial No. 320,985

3 Claims. (Cl. 255—71)

My invention relates to well drills and more particularly to means upon such drills for directing the course of the flushing fluid relative to the cutters.

In well drills the flushing fluid, employed in clearing the cutters of the cuttings and carrying said cuttings to the surface, is normally filled with abrasive particles, sand and the like. This fluid circulates at high speed and under high pressure and the sand tends to cut the metal of the bit. Hard metal is employed in the fluid discharging nozzles and in the cutters to resist this wear. However, the flushing fluid is deflected laterally upon contact with the cutters and is forced in around the bearings of the cutters so strongly that undue wear upon the bearings is experienced. The bearings are found to be cut away by the flushing fluid so that their normal life is materially shortened. The bearings normally are subjected to heavy wear due to the weight of the drilling string upon the bit and the rotation of the drill, but due to the strong circulation of mud about the bearings, further wear results and the bearings and interior of the cutters do not last during the life of the teeth upon the cutters.

It is an object of the invention to provide a deflecting means upon the drill which will be engaged by the stream of flushing fluid and direct the said fluid away from the bearings.

I aim to form adjacent the base of a rotating cutter, a baffle which directs the flushing fluid laterally toward the bit head, and away from the cutter bearings and still efficiently cleans the teeth of the cutter. The invention also includes a deflecting recess in the body of the drill.

In the drawing herewith Fig. 1 is a central longitudinal section through one section of a three cone bit embodying the normal type of bit and illustrating the course of the flushing fluid where my deflecting recess is employed.

Fig. 2 is a perspective view of the cutter shaft and adjacent portion of the bit head with my deflecting plate and recess both employed thereon.

Fig. 3 is a broken sectional detail showing the manner in which the flushing fluid is diverted away from the cutter bearings.

The drill to which my invention is applied in the drawing is a well known type of drill in which the head is formed in three longitudinal sections, each equipped with a cutter shaft and a conical shaped cutter thereon. In Fig. 1, one such section is shown. The body portion 1, has an upwardly tapered and threaded shank 2 and the lower end is inclined downwardly and outwardly

on its inner face 3. Upon this face is a downwardly inclined cutter shaft 4. Three such sections are fitted and welded together for connection to a drill collar for drilling.

The cutter shaft has raceways 5 and 6 formed therein to receive the rollers 7 and balls 8 respectively. At the end of the shaft is a recess into which is pressed a hard metal pilot pin 9. An approximately conical shaped cutter 10 is fitted over the end of the shaft. It has raceways to receive the bearings in the usual manner. Surrounding the pilot pin 9 in the cutter is a hard bearing ring or bushing 11. After the cutter has been placed upon the shaft the balls 8 are inserted into position in the raceways 6, through a bore 12 which is then filled with a plug 13 which is then locked against removal by welding material.

The cutter is formed with circumferential rows of cutting teeth 14 thereon in a manner well known in the art. The cutter wall has a fluid circulating opening 15 therein and it will be understood that the flushing fluid will fill the spaces on the interior of the cutter about the bearings so as to reduce friction and keep the bearings cool.

The flushing fluid is discharged against the surface of each cutter adjacent the base thereof through a discharge nozzle 16. As shown in Fig. 1 the fluid engages the cone surface and is deflected laterally, part of the stream being directed against the bit head at the larger end or base of the cutter. To deflect the fluid away from the bearings, I form a recess 17 in the face 3 to receive said stream and divert it upwardly. Thus only a small amount of the mud will flow down about the base of the cone and around the bearings. The larger portion will enter the recess 18 in the bit head and be deflected back. The portion of the stream that circulates into the space about the base of the cutter is insufficient to cause excessive wear upon the bearings such as would otherwise result from the splashing of the fluid in the direction of the shaft.

To further alleviate this wear upon the bearings, I may place a baffle or deflector plate 19 upon the inner face 3 of the bit head and about the upper outer rim of the cutter. This plate 19 is best seen in Fig. 2. It extends in the arc of a circle about the upper portion of the shaft and is spaced therefrom to allow space for the cutter. This plate may be in the form of a flange formed integral with the head as shown in Fig. 3 or it may be welded in place after the head is formed as will be obvious from Fig. 2.

When thus formed upon the head the plate will act, as seen in Fig. 3, to prevent the contact of the lateral stream of mud from engaging within the space between the surface 3 of the head and the base of the cutter and thus entering about the cutter bearings. The lateral stream will be diverted by the flange or plate into the recess 18 and from thence back toward the axis of the drill. The flange when separately formed may be of a hard wear resisting material which will endure during the life of the cutting surface of the drill and will prevent undue wear upon the bearing surfaces previously experienced due to the flushing fluid.

What I claim is:

1. In a well drill having a head, cutter shafts thereon, cutters on said shafts and a nozzle to discharge flushing fluid upon said cutters; the combination of a deflector plate on said head about the upper portion of each of said cutters 20

to be engaged by the flushing fluid discharged by said nozzle to direct the course of said fluid away from the bearings of said cutters.

2. In a well drill having a head, a cutter shaft thereon, a cutter rotatable on bearings on said shaft and a nozzle to discharge flushing fluid upon said cutter, the combination of a recessed and curved wall upon said head to receive a portion of the stream of flushing fluid and deflect it upwardly and a deflecting plate on said head below said recessed portion of the wall to divert said fluid.

3. In a well drill a head, a downwardly and outwardly inclined surface thereon, a cutter shaft projecting from said surface, a cutter rotatable on said shaft, a fluid discharge nozzle to deliver flushing fluid upon said cutter, an arcuate flange formed on said surface conforming to the outer curvature of said cutter, said flange acting to divert flushing fluid away from said shaft.

FLOYD L. SCOTT.
